UNITED STATES PATENT OFFICE

LAWRENCE DINKELSPIEL, OF WEST NEW YORK, NEW JERSEY

DESIGN FOR AN EMBROIDERED LACE SCARF OR SIMILAR ARTICLE

Application filed November 13, 1930. Serial No. 37,632. Term of patent 3½ years.

To all whom it may concern:

Be it known that I, LAWRENCE DINKELSPIEL, a citizen of the United States of America, residing at West New York, in the county of Hudson and State of New Jersey, have invented a new, original, and ornamental design for embroidered Lace Scarf or Similar Article, of which the following is a specification, reference being had to the accompanying drawing, forming part thereof.

The figure of the drawing is a plan view of approximately one half of the embroidered lace scarf of similar article showing my new design, the other half being a repetition thereof in reverse position.

I claim:

The ornamental design for an embroidered lace scarf or similar article, as shown and described.

LAWRENCE DINKELSPIEL.
